ELASTIC FABRIC

Filed Jan. 11, 1936

FIG. 1.

FIG. 2.

INVENTOR:
August K. Strupp,
BY *John C. Oechinger*.
ATTORNEY.

UNITED STATES PATENT OFFICE

98,740

DESIGN FOR ELASTIC FABRIC

August K. Strupp, Reading, Pa., assignor to The
Narrow Fabric Company, West Reading, Pa., a
corporation of Pennsylvania

Application January 11, 1936, Serial No. 60,528

Term of patent 14 years

To all whom it may concern:

Be it known that I, August K. Strupp, a citizen of the United States of America, residing at Reading, in the county of Berks and State of Pennsylvania, have invented a new, original, and ornamental Design for an Elastic Fabric, of which the following is a specification, reference being had to the accompanying drawing, forming part thereof.

Figure 1 discloses a portion of elastic fabric embodying my ornamental design, to which no tension is applied.

Fig. 2 discloses a portion of the elastic fabric

depicted in Fig. 1, as it appears when subjected to tension substantially equivalent to that incident to normal use.

The figures disclose the elastic fabric enlarged to approximately one and one-half times normal size, so that they will be approximately full size upon the reduction of the same to the ultimate size as appearing in the patent copy.

I claim:

The ornamental design for elastic fabric as shown and described.

In testimony whereof I affix my signature.

AUGUST K. STRUPP.
